UNITED STATES PATENT OFFICE.

MILTON B. HOOD, OF LYNN, ASSIGNOR TO M. C. HOOD & CO., OF BOSTON, MASSACHUSETTS.

DESIGN FOR A PERFUMERY-BOTTLE.

Specification forming part of Design No. 14,149, dated April 8, 1879; application filed February 26, 1879.
[Term of patent 3½ years.]

To all whom it may concern:

Be it known that I, MILTON B. HOOD, of Lynn, of the county of Essex and State of Massachusetts, have invented a new and ornamental Design for a Perfumery-Bottle; and I do hereby declare the same to be described in the following specification and represented in the accompanying drawings, of which—

Figure 1 is a front elevation, Fig. 2 a longitudinal and transverse section, and Fig. 3 a horizontal and transverse section, of a bottle formed in accordance with my said design, in the carrying out of which I make the body A of the bottle circular, with flat or slightly-concave opposite sides, a a, and a round or semicircular periphery, b, one or both of the sides being paneled, as shown at c, and all being essentially as represented, the neck d of the bottle being of the usual shape, as shown.

I claim—

The ornamental design, substantially as set forth, for the body of the perfumery-bottle, it being flat, paneled, and circular, as described, and having a periphery round or semicircular transversely thereof, all as shown and described.
